Primary Examiner — Michelle E. Wilson

Assistant Examiner — Clare Ann Gannon

(57) **CLAIM**

The ornamental design for a raised mat, as shown and described.

DESCRIPTION

FIG. 1 is a perspective view of a raised mat showing my new design;
 FIG. 2 is another perspective view thereof;
 FIG. 3 is a front view thereof;
 FIG. 4 is a back view thereof;
 FIG. 5 is a top view thereof;
 FIG. 6 is a bottom view thereof;
 FIG. 7 is a right-side view thereof;
 FIG. 8 is a left-side view thereof; and,
 FIG. 9 is a cross-sectional view marked off as in FIG. 5, wherein the dense shading represents the cross-sectional area.

1 Claim, 7 Drawing Sheets
